UNITED STATES PATENT OFFICE.

DANIEL J. MURNANE, OF CHICAGO HEIGHTS, ILLINOIS.

WINDOW VENTILATOR.

Application filed January 5, 1921. Serial No. 435,134.

To all whom it may concern:

Be it known that I, DANIEL J. MURNANE, a citizen of the United States, residing at Chicago Heights, in the county of Cook and State of Illinois, have invented a new and useful Improvement in Window Ventilators, of which the following is a specification.

My invention relates more particularly to ventilators of the type employing a plate-like portion, either rigid or flexible, which is positioned on the inside of a room, adjacent the window sill of a window and in spaced relation to the window sash, thereby to afford, when a window is partially raised, a deflecting surface which serves to cause the air entering the window to be deflected upwardly into the room and thereby avoid drafts.

My primary objects are to so construct the device that, when not in use, the parts thereof may be caused to occupy a position in which they are out of the way and will present a slight appearance, and be readily moved into operating position; to provide a construction of such device that it may be manufactured economically and shall be simple of structure; and other objects as will be manifest from the following.

Referring to the accompanying drawings: Figure 1 is a face view, taken from the interior of a room, of a window in the wall thereof, showing it as equipped with a ventilator embodying my invention, the central portion of the structure shown being broken away. Figure 2 is an end view of the structure shown in Fig. 1, this view being taken from the right hand side of Fig. 1. Figure 3 is a section taken at the line 3 on Fig. 1 and viewed in the direction of the arrow. Figure 4 is a section taken at the line 4 on Fig. 3 and viewed in the direction of the arrow; and Figure 5, a broken perspective view of one end of the upper portion of a curtain employed in the structure of the figures now being described.

Referring to the construction shown which illustrates the preferred embodiment of my invention, a window-frame of a window to be equipped with the device is represented at 11, the lower sill of which is shown at 12, there being mounted within the frame 11 to slide up and down therein, a window sash 13 containing the glass pane 14.

The particular structure of ventilator shown is formed of plates arranged to be

located at opposite sides of the window-frame 11 and extend, when in operating position, at angles thereto and into the room, each of these plates being formed of sections 14 and 15. The sections 14 which are shown as being permanently secured to the window-frame to extend inwardly therefrom, are shown as of general rectangular shape having ears 16 stamped from the metal thereof, and together with the rearwardly-extending portions 17 of these plate sections, fit over the corner of the adjacent uprights of the window-frame, the plate-sections being shown as rigidly secured in such position by means of screws 18 and 19. The plate-sections 14 preferably fit closely against the top side of the window sill 12, and preferably extend a slight distance inwardly therefrom as shown. The plate-sections 15 are shown as of general triangular shape with their upper edges curved as represented, the plate-sections 15 being hingedly connected with the plate-sections 14, as through the medium of the hinges represented at 20 and secured to these respective sections, the hinges being of such construction that the plate-sections 15 may be swung on the plate-sections 14 to extend adjacent, and in generally parallel relation, to the adjacent uprights of the window frame 11. In other words, the plate-section 15 at the right hand side of Fig. 3 may be swung in counter-clockwise direction to extend generally parallel with the sill 12, and the plate-section 15 at the left hand side of this figure may be swung in a clockwise direction to cause it to extend generally parallel with the sill 12, the hinges 20 being preferably spring hinges in order that the sections 15 may swing on the hinges in the respective directions stated, when the other parts of the structure hereinafter described, are manipulated, in the operation of moving the parts of the structure out of operating position.

Located at the inner surfaces of the plate structure referred to, are the channel bars represented at 21, these channels opening toward each other. Bars 21 are pivotally connected at their lower ends, as through the medium of the pivot pins 22, with the adjacent plate-sections 14, the upper ends of these bars being provided with outwardly-turned ends 23 which extend over the upper edges of the plates referred to and overlap their outer sides, being spaced therefrom sufficiently to permit of the

swinging of these bars on their pivots for a purpose hereinafter described. The portions 23 are connected by a pin-and-slot connection with the outer ends of levers 24 located at the outer surfaces of the plates referred to and pivotally connected at 25 with the stationary plate-sections 14, the pin-and-slot connection shown comprising, as to each of the connections, a pin 26 on the 10 bar portion 23 and a slot 27 in the adjacent lever 24 into which the pin 26 extends.

It will be understood from the drawings and the foregoing description that the bar and lever structure just described, serves as 15 a means for holding the plate-sections 15 and 14 in aligned condition and against relative swinging movement, when the bars 21 are swung outwardly to the position shown in the drawings, in which position, 20 it will be noted, these bars and levers extend across the joints between the plate-sections, and when these bars and levers are swung toward the window, to a position in which they extend substantially vertical and 25 are out of a position in which they overlap the sections 15, the latter are free to swing on their hinges 20 in the respective directions hereinbefore described, by reason of the action of the springs in the hinges.

30 In the particular construction illustrated the bars 21 serve as a swinging holder for the front, or deflecting side 28 of the ventilator, which may be, and preferably would be, a pane of glass, mounted in a frame, or 35 not, as desired, the deflecting surface 28 extending at its ends into the channels in the bars 21, and, by reason of the arrangement of the bars, as hereinbefore described, being readily movable from deflecting position, represented in Fig. 2, in which position the pins 26 are shown as engaging the outer ends of the slots 27, to a position in which it extends substantially vertically closely adjacent the window. It would be preferred that the deflecting surface 28 be of 40 transparent material because, in accordance with the preferred embodiment of my invention, this section would remain operatively connected with the window-frame, 45 when not being used as a deflector surface.

50 It will be understood from the foregoing that when the parts are in the position shown in the drawings and the window 14 is raised, preferably not above the upper edge of the deflector surface 28, the air passing through the open portion of the window will strike the deflecting portion 28 and thereby be deflected upwardly into the upper portion of the room.

55 The device now being described, is also provided with a curtain device involving the use of a flexible sheet rolled upon a circular roller represented at 29 and journaled at its ends in brackets 30 secured to the 60 window frame below the window sill 12.

The roller device 29 may be the same as that used for window shades and present the automatic shade rewinding feature. The curtain, represented at 31, may be of material either transparent or opaque to light, 70 its free edge being provided with a stiffening strip represented at 32 as is common in shade constructions, and equipped at its opposite ends with clips represented at 33 and shown of hook form adapted to hook 75 over inwardly-turned flanges 34 on the outer edges of the plate-sections 15. The curtain 31 is of such width, that when it is upwardly drawn on at its free edge portion to partially unroll it, it will extend adjacent the upwardly-inclined edges 35 of the plate-sections 15, the curtain being held in such position, in which it extends in an upwardly-inclined direction from the window toward the center of the room, by the engagement of the hook portions of the clips with the upper edges of the flanges 34 as stated.

In practice the device may be provided with both the deflecting section 28 and the 90 curtain 31 permitting the user to use either one of these portions as a deflecting surface, as desired either by reason of possible impairment of one, or as a matter of choice, or employing the curtain section as a means 95 of obstructing the view through the lower portion of the window in which case the curtain would be of opaque material. If desired, the section 28 may be of opaque material to obstruct the view through the lower 100 part of the window, and where it is desired to have the section 28 of transparent material, the use of the curtain 31 would be quite desirable especially where the device is installed in dwellings.

105 While the two portions 28 and 31 may be used, under some conditions, to advantage in the same structure, it will be understood that so far as certain features of the structure are concerned the deflecting surface 28 110 or the surface 31 may be omitted, and where the portion 28 is omitted the curtain 31 would form the air-deflecting surface. When the curtain 31 is not in use it would assume the rolled condition represented in 115 Fig. 4 and by reason of its location, it is more or less obscured from view.

120 The provision of the bars 24 pivoted to the plate-sections 14 at points above the pivotal support of the bars 21 is of advantage as thereby the hinged plate sections 15 are firmly braced in extended position.

125 While I have illustrated and described a certain particular construction in which my invention is embodied, I do not wish to be understood as intending to limit my invention thereto as the invention may be embodied in other structures, and the structures as shown may be modified and altered 130 without departing from the spirit of my in-

vention, it being my intention to claim my invention as fully and completely as the prior state of the art will permit.

What I claim as new and desire to secure by Letters Patent is:

1. The combination with a window frame, of members located at opposite sides of the window opening therein adjacent the lower portion of the latter, said members being pivotally supported to adapt them to be swung outwardly and backwardly in a substantially horizontal plane toward the window frame, an air-deflecting member extending across the space between said pivoted members at the inner edges thereof, and means for holding said first-referred-to members in a position in which they extend substantially at a right angle to the plane of the window opening in all of the different adjustments of said air-deflecting member relative thereto.

2. The combination with a window-frame, of members located at opposite sides of the window-opening therein adjacent the lower portion of the latter, said members being pivotally supported to adapt them to be swung outwardly and backwardly toward the window frame, an air-deflecting member located between said first-referred-to members, and bars pivoted at their lower ends to a stationary part of the structure adjacent said first-referred-to members and adapted to be swung at their upper ends toward and away from the window-opening, said air-deflecting member engaging, and being movable with, said bars, said bars extending into overlapping position relative to said first-referred-to members when swung away from the window-opening and serving to hold said members at an angle to the plane of the window-opening and disengaging from said first-referred-to members for permitting backward movement of the latter, when swung toward the window-opening.

3. In a structure of the character referred to, the combination of pivotally-supported members spaced apart and forming the sides of the deflector, an air-deflecting member, and means pivotally supporting said air-deflecting member in the space between said members, said means comprising bars engaging said air-deflecting member and pivoted to a part stationary relative to said pivotally-supported members, and a link operatively connected with one of said bars and adapted in one position to extend across the joint between the adjacent one of said first-named members and the part to which the latter is pivoted.

4. In a structure of the character referred to, the combination of pivotally-supported members spaced apart and forming the sides of the deflector, an air-deflecting member, and means pivotally supporting said air-

deflecting member in the space between said members, said means comprising bars engaging said air-deflecting member and pivoted to a part stationary relative to said pivotally-supported members, and a link 70 operatively connected with one of said bars at a point above the pivoted support for said bars and adapted in one position to extend across the joint between the adjacent one of said first-named members and the 75 part to which the latter is pivoted.

5. The combination with a window-frame, of members located at opposite sides of the window-opening therein adjacent the lower portion of the latter, said members being 80 pivotally supported to adapt them to be swung backwardly in a substantially horizontal plane toward the window-frame, means pivotally supported on a stationary part of the structure adapted to be moved 85 into and out of engagement with said members for holding the latter in a position in which they extend at an angle to the plane of the window-opening and an air-deflecting member mounted to be movable between 90 said first-referred-to members toward and away from the window-opening in the set position of said first-referred-to members.

6. The combination with a window frame 95 of members located at opposite sides of the window opening therein adjacent the lower portion of the latter, said members being pivotally supported to adapt them to be swung into and out of a position in which they extend substantially at right angles 100 to the plane of the window opening, an air-deflecting member extending across the space between said first-referred-to members, means pivotally connected with a stationary part of the structure for supporting 105 said air-deflecting member, links pivotally mounted on a stationary part of the structure above the pivotal support of said means and located at the outer faces of said first-referred-to members and operatively engaging 110 said means, said links in the movement of said air-deflecting section into substantially vertical position, moving out of a position in which they obstruct the swinging of said first-referred-to members backwardly.

7. The combination with a window frame, of stationary members located at opposite sides of the window opening therein adjacent the lower portion of the latter, wings 120 pivotally supported on said stationary members to adapt them to be swung into and out of a position in which they extend substantially at right angles to the plane of the window opening, bars located at the inner faces of said wings, pivotally supported at their lower ends on a stationary part of the structure to swing back and forth toward and away from said window opening in the space between said wings, an air- 125 130

deflecting member engaging said bars and movable therewith, said bars being provided at their upper ends with recessed portions adapted to receive the upper edges of 5 said wings when the latter extend at substantially right angles to the plane of the window opening, links located at the outer faces of said wings and pivotally supported on said stationary members at points above 10 the pivotal supports for said bars and so disposed that when said wings are positioned as last stated, said links will extend

across the joints between said stationary members and said wings, said links engaging said recessed portions of said bars at the 15 outer ends of said links, the engagement between these parts permitting relative movement thereof, the parts being so constructed and arranged that when said air-deflecting member is swung to substantially closed 20 position, said recessed portion of said bars and said links will be out of engagement with said wings.

DANIEL J. MURNANE
